(57) **CLAIM**

The ornamental design for a jacket, as shown and described.

DESCRIPTION

FIG. 1 is a first perspective view of the jacket embodying the new design;

FIG. 2 is a second perspective view thereof; and,

FIG. 3 is a front view thereof.

FIGS. 1-3 show portions of a jacket in broken lines that do not form any part of the claimed design. Further, the broken lines immediately adjacent the solid-line portions of the design form the boundary of the design, with the broken lines forming no part of the claimed design.
